Lacy & Lacy, Attorneys

UNITED STATES PATENT OFFICE.

CHARLES F. ROOD, OF SUTHERLIN, OREGON.

SMOKING PIPE.

Application filed June 29, 1926. Serial No. 119,498.

This invention relates to smoking pipes and more particularly to an improved stem construction, one object of the invention being to provide a pipe which may be very easily cleaned if the stem becomes choked with tobacco and nicotine.

Another object of the invention is to provide the stem with a liner which may be readily removed therefrom when it is desired to clean the pipe and in addition to constituting a removable liner also serves as a coupling to detachably connect a mouth-piece with the pipe stem.

Another object of the invention is to provide a liner formed of separable sections which may be firmly held in operative relation to each other but readily taken apart when withdrawn from the pipe stem.

This invention is illustrated in the accompanying drawing, wherein

Figure 1 is a longitudinal sectional view through the improved pipe;

Fig. 2 is a perspective view of the liner and a sleeve which holds the companion sections thereof assembled;

Fig. 3 is a transverse sectional view taken on the line 3—3 of Fig. 1.

The pipe forming the subject-matter of this invention includes a bowl 1 which may be of any desired size and configuration and is provided with a stem 2 which projects from its lower portion and is formed with an enlarged bore 3 communicating with the bottom of the bowl. The mouth-piece 4 is also of a conventional construction and formed with the usual bore or smoke passage 5. At its forward end the mouth-piece is reduced to provide a neck extension 6 surrounded at its rear end by an annular abutment shoulder 7. In order to connect the mouth-piece with the stem, there has been provided a coupling which in addition to joining the mouth-piece to the stem also constitutes a removable liner or filler for the stem.

This coupling is constructed as shown in Fig. 2 and comprises companion sections 8 which may be formed of any suitable material and are separable. The two sections, when disposed in cooperating relation to each other, form a tube 9 which fits snugly

within the bore 3 of the stem and has its bore 10 axially aligned with the bore 5 of the mouth-piece and communicating with the bottom of the bowl 1. The outer end portion of the companion sections 8 are enlarged, as shown at 11, and cooperate to form a socket 12 which at its forward end abuts the rear end of the stem 2. The socket tapers rearwardly, as shown in Fig. 1, so that it may have wedging fit into a tapered sleeve 13. The sleeve 13 is formed of metal and at its rear end is provided with an inwardly extending annular flange 14 which overlaps the rear edge of the socket and is adapted to be firmly gripped between the rear edge 65 of the socket and the abutment shoulder 7 when the neck 6 of the mouth-piece is fitted into the socket. The neck fits snugly into the socket and from an inspection of Fig. 1 it will be readily seen that a tight joint will 70 be formed and leakage prevented which would interfere with proper drawing of the pipe. The sleeve 13 may terminate at the forward end of the socket, but in the preferred form it is extended somewhat and 75 has overlapping engagement with the pipe stem so that danger of the liner being broken at the junction of the tubular portion 9 with the socket 12 will be eliminated.

By having the pipe constructed as illustrated it can be readily cleaned as it is merely necessary to grasp the sleeve 13 with the fingers of one hand and the bowl and stem portion of the pipe with the other hand and exert a pulling action to withdraw the liner from the stem. After the liner has been withdrawn, the mouth-piece may be extracted from the socket and the sleeve removed. The two sections of the liner may then be separated and thoroughly cleaned. 80 After they have been cleaned, the coupling may be reassembled and engaged with the mouth-piece and fitted into the pipe stem. If only the mouth-piece needs cleaning, it may be removed from the socket without 85 withdrawing the coupling from the stem.

Having thus described the invention, I claim:

A smoking pipe comprising a bowl, a stem extending therefrom and having a bore com-

municating with said bowl, a tubular liner removably fitted into the bore of said stem and having its rear end portion enlarged to overlap the rear end of the stem, said liner consisting of longitudinally extending separable sections, a sleeve fitted upon the enlarged rear portion of said liner and pro-

vided with an inwardly extending annular flange overlapping the rear end of the liner and a mouth-piece having a reduced forward end fitted into said liner and an annular shoulder engaging the flange of said sleeve.

In testimony whereof I affix my signature.
CHARLES F. ROOD. [L. S.]
